UNITED STATES PATENT OFFICE.

DAVID S. STEWART, OF MORRIS, WISCONSIN.

TRACTION-ENGINE.

SPECIFICATION forming part of Letters Patent No. 484,829, dated October 25, 1892.

Application filed May 11, 1892. Serial No. 432,554. (No model.)

To all whom it may concern:

Be it known that I, DAVID S. STEWART, a citizen of the United States, and a resident of Morris, in the county of Shawano, and in the State of Wisconsin, have invented certain new and useful Improvements in Traction-Engines; and I do hereby declare that the following is a full, clear, and exact description thereof.

10 My invention relates to new and useful improvements in traction-engines; and it consists in the matters hereinafter described, and pointed out in the appended claims.

In the accompanying drawings, illustrating 15 my invention, Figure 1 is a top plan view of a pair of trucks constructed in accordance with my invention. Fig. 2 is a side elevation of the traction-engine complete and illustrates certain portions of the mechanism as 20 broken away to better illustrate details of construction. Fig. 3 is a vertical cross-section of one of the trucks, taken on line 3 3 of Fig. 1.

In said drawings, A represents the boiler of 25 a traction engine or locomotive, and B B the engines for transmitting motion to the traction mechanism.

C is a crank-shaft extending lengthwise of the machine and operatively engaged with 30 the pitmen b b of the steam-engines B B by means of cranks c c, said shaft extending from one truck to the other and being operatively engaged with the traction devices through the medium of suitable intermediate gearing, 35 as will be presently described.

The two trucks D D each carry two traction-wheels E E, loosely journaled upon opposite ends of a transverse axle E', upon the central portions of which the boiler is supported 40 by means of suitable fifth-wheel connections e' e', so as to enable the trucks to be turned from side to side beneath the boiler. Rods d d are engaged with ears or lugs d' d' on the rear end of the front truck and the front end 45 of the rear truck, said rods being each arranged diagonally and engaged with the said ears or lugs which are located at opposite sides of the two trucks, this arrangement of parts being such that by a movement of one 50 of the trucks to the right the other truck will be turned toward the left to a corresponding extent.

Power is applied to the traction-wheels E E by means of suitable gears and traction-chains, substantially of the same general construction as that set forth in a prior application, filed by me on the 21st day of December 1891, and Serial No. 415,712, the same consisting, essentially, of a sprocket-gear F, over which the traction-chain is passed and to 55 which power is applied to propel said chain, and the traction-wheels E E being each provided with an annular groove e, within which the said chain runs, and the chains being also each preferably trained over a second sprocket-gear F', as shown, the latter being employed simply to carry the chain and running as idlers, as fully described in my said prior application.

My present invention relates more particularly to the mechanism for communicating motion to the sprocket-gears F F, and for this purpose the two gears F F at opposite sides of each truck are mounted on independent shafts F² F², arranged in line with 70 each other and receiving power from the crank-shaft C by means of a differential gear, by means of which both of said shafts F² F² are actuated, but are permitted to rotate at different rates of speed, so as to 75 enable the machine to be turned about in a very small space without throwing either of the traction-gears of either truck out of operation. This differential gear comprises a bevel-pinion H, operatively engaged with the 80 crank-shaft C and meshing with a bevel-gear I, which is loosely mounted on the axis of the sprocket-gears F F, this latter gear carrying two or more smaller planetary gears I' I', 85 which each mesh at opposite sides with bevel-gears J J, respectively keyed to the two shafts F² F², upon which the sprocket-wheels F F are mounted. By this construction power being applied to rotate the pinion H will obviously cause the gear I to revolve, and this 90 gear carrying the planetary gears I' I', which are in mesh at opposite sides with the gears J J, will operate to revolve both of said gears J J in the same direction, while at the same time permitting one of the said wheels to 95 revolve faster than the other, so as to cause a more rapid movement of the traction-chain carried by the wheel which is located upon the other end of the shaft upon which said

wheel is keyed when such movement becomes necessary in turning a corner, but carrying the said gears J J around at a uniform rate of speed when such unequal movement is not produced by turning the trucks.

As illustrated in the drawings, the crank-shaft C is connected with the gears H H at its opposite ends by means of sleeves C' C', having square or angular openings therein, the ends of the said crank-shaft being similarly shaped and arranged to slip within said sleeves, so as to accommodate the movements of the trucks, and these sleeves being each connected by a universal joint c' with the end 15 of the shaft C² upon which the gear H is secured, this shaft being suitably journaled in a bearing h in the frame of the truck.

As illustrated in the drawings, I prefer to arrange the crank-shaft along one side only 20 of the engine and to arrange the two driving-pinions H H, actuated thereby, so as to mesh with different sides of the gears I I, so that a rotation of the crank-shaft will operate to turn both sets of gears in the same direction.

25 In order to provide a simple steering device for guiding the machine, I locate a winding-drum K at a convenient point upon the forward end of the machine, said drum being journaled upon arms k² k² on the boiler A, 30 and to the axis of said drum secure a revolvable shaft K', which extends upwardly through suitable bearings and is provided at its upper end with a hand-wheel K², as shown in the drawings, cords k k being arranged to wind upon the 35 drum K and each of said cords being connected with an ear k' upon one side of the front part of the truck. It follows from this construction that by rotating the hand-wheel K² in the desired direction the cords k k may be 40 wound upon or unwound from the drum, so as to turn the front truck and guide the machine in the desired direction, the oblique connections between the two trucks obviously operating to turn the rear truck in the opposite 45 site direction.

By my improvements I am enabled to construct a very compact and simple form of actuating mechanism for communicating motion to the traction devices and am enabled to dispense entirely with the engines upon one side 50 of the machine, the traction devices at both sides of the machine being operated from the engines at one side of the boiler instead of necessitating the use of separate engines for 55 actuating the traction devices at each side of the machine.

Having thus described my invention, what I claim as new, and desire to secure by Letters Patent of the United States, is—

1. In a traction - engine, the combination, 60 with the boiler and actuating-engine, of one or more trucks provided upon opposite sides with suitable traction devices, each comprising a suitable traction-wheel, a traction-chain trained over the same, and a drive-wheel for 65 operating said chain, two shafts upon which said drive-wheels are mounted, and a differential gear between the crank-shaft of the engine and said shafts, substantially as and for the purpose described. 70

2. In a traction-engine, the combination, with the boiler, the engine, and its crank-shaft, of two trucks connected together at their adjacent ends by diagonal rods, traction devices upon opposite sides of each of said trucks, each of said devices comprising a traction-wheel, a chain trained over said wheel, and a drive-wheel for giving a longitudinal motion to said chain, two shafts extending transversely and arranged end to end in each 80 truck and each carrying the drive-wheel at one side of the truck, and a differential gear connecting the adjacent ends of the said transverse shafts in each truck with one end of the crank-shaft of the engine, substantially as described. 85

3. In a traction - engine, the combination, with the boiler, the engine, and its crank-shaft, of two trucks flexibly connected together at their adjacent ends by diagonally- 90 arranged rods, traction devices located upon opposite sides of each of said trucks and each comprising a traction-wheel, a traction-chain trained over said wheel and an actuating-wheel engaged with said chain, transverse 95 shafts arranged end to end and in line with each other in each truck and each carrying at its outer end one of the said drive-wheels, sleeves having sliding engagements with opposite ends of the crank-shaft of the engine, 100 but non-rotative thereon, and a differential gear connecting each of said sleeves with the transverse shafts in one of the trucks, substantially as and for the purpose described.

In testimony that I claim the foregoing I 105 have hereunto set my hand, at Shawano, in the county of Shawano and State of Wisconsin, in the presence of two witnesses.

DAVID S. STEWART.
